UNITED STATES PATENT OFFICE.

CHARLES H. BUSCH, OF KENOSHA, WISCONSIN, ASSIGNOR OF ONE-HALF TO ADAM ZEYEN, OF KENOSHA, WISCONSIN.

SPRINKLER.

1,036,793.

Specification of Letters Patent. Patented Aug. 27, 1912.

Application filed September 19, 1911. Serial No. 650,114.

To all whom it may concern:

Be it known that I, CHARLES H. BUSCH, a citizen of the United States, residing at Kenosha, in the county of Kenosha and State of Wisconsin, have invented new and useful Improvements in Sprinklers, of which the following is a specification.

My invention relates particularly to sprinklers adapted for sprinkling lawns and gardens; and my primary object is to provide a device of exceedingly simple character adapted to be manufactured at small cost and thoroughly effective for its purpose.

The device is shown in its preferred embodiment, in the accompanying drawing, which illustrates the same by a sectional view, the supporting rod or standard being shown brokenly.

The device comprises a cast metal, hollow head or member 1; a surmounting sheet metal member 2; and a sheet metal union 3 connected with the base portion of the member 1. The member 1 is formed with a contracted throat portion 4 having a reduced extension 5 with which the member 3 is connected. The upper or outlet end of the member 1 is flaring or enlarged and is equipped at its mouth with an external bead or flange 6. The member 2 is stamped into approximately hemispherical form and is provided with an outwardly extending flange 7 which is curved downwardly and clenched about the bead or flange 6. Said member 2 is provided with a series of perforations 8 which are adapted to produce circular series of jets of water.

The member 3 may be stamped of sheet metal, being formed in this operation into tubular form, but provided with a helical corrugation 9, forming a thread into which the threaded nipple of a hose may be screwed. The inner end of the member 3 is provided with an inturned flange 10 which is re-curved, as shown at 11. The flange 11 encircles the reduced portion 5 of the member 1; and the end portion of the part 5 is spun outwardly, as indicated at 12, to engage the flange 11. Thus a secure connection is afforded.

The member 1 has a lug 13 cast on its base portion, preferably at the outer or convex side of the throat 4; and through the medium of said lug, the device is mounted on a stake or standard 14, which is adapted to be thrust into the ground to support the device in any desired position, while the sprinkling operation is being performed.

The device described is exceedingly simple, may be manufactured cheaply, and performs admirably the function for which it was devised.

It is preferred to make the tip 2 either of galvanized sheet metal or brass; and the member 3 may be made of brass or galvanized sheet metal, preferably brass, while the member 1 may be of cast iron.

What I regard as new and desire to secure by Letters Patent is—

1. A spraying-device for attachment to a hose, comprising a hollow cast metal member having a throat portion equipped with a reduced extension disposed at an obtuse angle to the axis of the head portion of said member and having an upper end equipped externally with a flange, a tubular member 70 having a spiral corrugation affording a thread for a hose connection and having at its inner end an inturned flange having spun connection with said reduced extension of said first-named member, and a perforated sheet metal tip-member having a flange embracing the flange of said first-named member.

2. A spraying device for attachment to a hose, comprising a hollow member having a 85 throat portion reduced adjacent its lower end, and having its front wall and a portion of its rear wall disposed on a curve coincident with the line of the entering stream of water, the remaining portion of the rear 90 wall being reversely curved to provide an enlarged chamber adjacent the point of discharge, and a spraying tip seated on the discharge end of said device.

CHARLES H. BUSCH.
